(57) **CLAIM**

The ornamental design for a hexagonal brick as shown and described.

DESCRIPTION

FIG. 1 is a perspective view of a hexagonal brick showing my new design; and,

FIG. 2 is a top plan view thereof.

The broken lines in the drawings depict environmental structure and form no part of the claimed design.

Perspective views of the design from different rotational angles relative to the perspective view of FIG. 1 are identical to FIG. 1 and are therefore not separately illustrated.

The bottom plan view is identical to the top plan view of FIG. 2 and therefore is not separately illustrated.

1 Claim, 2 Drawing Sheets
